UNITED STATES PATENT OFFICE

ALPHEUS O. HURXTHAL, OF PHILADELPHIA, PENNSYLVANIA, ASSIGNOR TO PROC-
TOR & SCHWARTZ, INCORPORATED, OF PHILADELPHIA, PENNSYLVANIA, A COR-
PORATION OF PENNSYLVANIA

TENTERING MACHINE

Application filed June 18, 1928. Serial No. 286,320.

This invention relates to tentering machines, and particularly to means for controlling the circulation of the drying air therein.

5 In machines of this character the goods to be dried is usually stretched taut in a horizontal plane between transversely spaced supports, which extend longitudinally of the machine, and the drying air forced through the goods in a vertical direction, the goods at the same time passing through the machine in a longitudinal direction.

There are times when this method of drying can not be employed, for example, in the drying of fine goods, such as silks, in which bowing of the goods between the supports, by the air being forced through the goods, will cause the fabric to split or tear, and also in the drying of materials which are so made 20 that the air can not be properly forced through the goods, as for example, wherein the material is covered by another sheet.

The principal object of this invention is to provide a machine which will be capable 25 of efficiently drying any and all classes of fabrics, by constructing the machine in such a manner that the air currents will be passed across the goods in a substantially horizontal direction and in contact with both faces of 30 the goods simultaneously. By this method the pressure of the air against the opposite faces of the goods is substantially equalized, which prevents bowing of the fabric between the supports.

35 Another object of the invention is to construct the machine in such a manner that the portion of the air passage therein, through which the goods travels, will be contracted or restricted in a manner to form, in effect, a nozzle, by means of which an increase in the 40 velocity of the air will be obtained adjacent the goods, thereby effecting a rapid drying of the said goods.

45 The construction of a machine made in accordance with the principles of the invention will be fully disclosed hereinafter, reference being had to the accompanying drawings, of which:

50 Fig. 1 is a diagrammatic longitudinal sec-

tional elevation through the machine taken on the line 1—1, Fig. 2;

Fig. 2 is a diagrammatic sectional plan view taken on the line 2—2, Fig. 1;

Fig. 3 is a transverse sectional elevation 55 taken on the line 3—3 of Fig. 2;

Fig. 4 is a transverse sectional elevation taken on the line 4—4, Fig. 2;

Figs. 5 and 6 are views similar to Figs. 3 and 4 respectively, showing a modification of 60 the invention; and

Figs. 7 and 8 are views similar to Fig. 3, showing still other modified forms of the invention.

Referring to Figs. 1 to 4 inclusive, the machine comprises a suitable casing 1 composed of side walls 2, 2, end walls 3, 3 and a roof 4, the casing 1 being mounted on a floor or similar support 5. A transverse partition 60 is located intermediate the end walls 3, 3, 70 which divides the interior of the casing 1 into two separate compartments 6 and 7 respectively.

At spaced intervals throughout the length of the casing 1 are located supports 8, 8, each 75 of which comprises a pair of vertical pedestals 9, 9 connected at their upper ends by a bridge element 10.

Extending longitudinally of the casing 1 and carried by the supports 8 is a pair of rails 80 11, 11, in the upper face of each of which is formed a pair of parallel longitudinally extending grooves 12. In the grooves 12, 12 of each rail 11 is suitably mounted a cable or chain 13 which passes around suitable 85 wheels 14, 14 which are rotatably mounted at the opposite ends of each of the rails 11. The chains or cables 13 are provided with vertically extending pins 15 which are adapted to pass through the opposite longitudinal edges 90 of a strip of material α which is to be dried. The rails 11, 11 with the conveyers 13 respectively carried thereby maintain a strip of material in a taut condition in a horizontal plane, as illustrated in Figs. 3 and 4. Any 95 suitable means, not shown, may be provided for driving the conveyers 13, 13 in unison in order that the strip of material will be carried through the machine.

Extending in a vertical plane and longitu-

100

dinally of the casing 1 is a partition 16, which is provided with a series of circular openings 17 in each of which is rotatably mounted a fan 18. Each fan is secured to one end of a shaft 19, the opposite end of which projects through one of the side walls 2 and is provided at its outer end with a pulley 19^a by means of which the fan is adapted to be rotated. The partition 11 extends from the floor 5 to a point below the under side of the adjacent supporting rail 11.

Intermediate the supporting rails 11, 11 is a suitable framework 20 on which is mounted a series of heating coils 21, 21.

Extending between the top edge of the partition 16 and the adjacent side of the framework 20 is a horizontally disposed partition 22, which divides the interior of the casing 1, at one side of the vertical partition 16, into a heating chamber 23 and a drying chamber 24. A circulating chamber 25 is formed between the vertical partition 16 and the adjacent side wall 2 of the casing 1.

The fans 18 located in the compartment 6 of the casing 1 are adapted to be rotated in one direction and thereby circulate the air in the said compartment in the direction indicated by arrows in Fig. 3, while the fans in the compartment 7 are adapted to be rotated in an opposite direction to circulate the air in the compartment 7 as indicated by the arrows in Fig. 4, whereby the goods α , in passing longitudinally through the casing 1, is subjected to air currents, first from one edge then from the opposite edge.

Rotation of the fans 18 in the compartment 6 will cause a circulation of air, as indicated by the arrows in Fig. 3, as above noted, the air being drawn from the circulating chamber 25 through the openings 17 in the partition 16 into the heating chamber 23, around the heating coil 21, thence upwardly into the drying chamber 24, returning to the circulating chamber 25 a passage formed between the top of the partition 16 and the roof 4.

Mounted on top of the framework 20 intermediate the rails 11, 11 is a horizontally extending baffle plate 26 which lies in a plane substantially parallel to and below the plane assumed by the material α as it passes through the machine. Parallel to the baffle plate 26 and located above the material α is a second baffle plate 27.

The air in circulation in the compartment 6 is directed between the baffle plates 26 and 27 by means of angularly disposed baffle plates 28 and 29. The angularly disposed baffle plate 28 is secured along one of its longitudinal edges to the roof 4 and along its opposite edge to a corresponding edge of the horizontal baffle plate 27. The angularly disposed baffle plate 29 is secured along one of its longitudinal edges to the corresponding edge of the horizontal baffle plate 26, and along its opposite edge to a bar 30 carried

by arms 31 extending laterally from the frame 20.

This construction produces an air nozzle 32 which contracts or restricts the air passage. The material to be dried is suspended substantially equidistant between the horizontal baffle plates 26 and 27 which form the upper and lower walls of the air nozzle. The pressure of air banked in the side of the drying chamber adjacent the angular baffles 28 and 29 is built up by the fan 18 and in seeking egress passes through the nozzle 32 at an increased velocity which effects a rapid drying of the goods α .

In the compartment 7 the air is circulated in an opposite direction across the goods α , as indicated in Fig. 4. In this compartment 7 the angularly disposed baffle plates 28^a and 29^a are at the opposite side of the horizontal baffles 26 and 27. The baffle 28^a extends from the edge of the horizontal baffle 27 to the roof 4 while the baffle 29^a extends from the corresponding edge of the horizontal baffle 26 to a point on the upper side of the horizontal partition 22 intermediate the vertical partition 16 and the frame 20. On the opposite side of the frame 20 is located a short vertical partition 33 which directs the air into the heating chamber 23 around the heating coils 21.

In the compartment 6 the air from the fans 18 is directed against the heating coils 21 by means of angularly disposed baffle plates 34 and 35 as indicated in Fig. 3.

From the above description, it will be noted that the air circulated by the fans 18 passes first through the heating coils 21, whereby the temperature of the air is raised, thence into the air nozzle 32, the flow of heated air being divided and passing across each of the opposite faces of the goods at substantially equal pressures on each side and at increased velocity, whereby bowing of the goods intermediate the supports is obviated, and a rapid drying of the goods is obtained.

As shown in Figs. 3 and 4, the temperature of the air as it passes through the restricted passageway 32 is raised or boosted by heating or booster coils 45 located in the passageway between the plates 26 and 27 and preferably below the strip of material located in the passageway.

Obviously the fans may be located at any desired point in the air passage without departing from the essential features of the invention, for example in Figs. 5 and 6 the fans are shown as being located on one end of the drying chamber and in Figs. 7 and 8 the fans are shown as being located at the center of the casing under the lower wall of the air nozzle.

In Figs. 5 and 6 the air nozzle 32^a comprises an upper horizontal baffle plate 26^b having an angularly disposed baffle plate 28^b, at each of its opposite edges, and a lower baffle plate

27^b composed of a pair of angularly disposed sections 29^b, 29^b.

The horizontal partition 22^b in this instance extends substantially across the entire 5 area of the casing joining with the lower edge of the vertical partition 16^b at one side and stopping short of the side wall 2 at the opposite side to provide a passageway 40 for the air between the heating chamber 23^b and the 10 drying chamber 24^b.

Exhaust fans 41 may be provided as indicated in Fig. 5 for extruding a certain percentage of the moist air, fresh air being admitted in any suitable and common manner, 15 such as screened openings in the side walls of the casing at the air-receiving side of the heating chamber.

In each of Figs. 7 and 8 the roof 4 of the 20 casing forms the upper wall of the air nozzle while the lower wall of the said nozzle is formed by a horizontal baffle plate located under the goods α , the circulating fans being located directly below the baffle plate, and the heating coils being located immediately adjacent the fans.

In Fig. 7 the heated air is directed from the heating coils 21^c between the under side of the fabric α and the upper side of the baffle 27^c by a depending baffle 36 on one edge of 30 the horizontal baffle 27^c, and a depending baffle 37 secured to one of the rails 11^c, the air for the upper side of the fabric passing around the outer edge of the rail 11^c and thence between the said upper side of the 35 fabric and the roof 4. A baffle 38 is located within the heating coil 21^c and directs a portion of the air flow upwardly between the baffles 36 and 37.

In Fig. 8, the air is circulated in an opposite direction from that shown in Fig. 7 and the rail 11^d is provided with a depending curved baffle 39 between which and a short depending flange 36^d on the horizontal baffle 27^d the air passes, the depending flange 36^d 45 on the opposite edge of the horizontal baffle 27^d directing the air downwardly onto the heating coils 21^d.

In each instance the portion of the air passage, through which the material to be dried is passing, is restricted or contracted with respect to the remainder of the air passage, thus a high velocity of the air is obtained in the restricted portion of the air passage and immediately adjacent both the opposite faces of the fabric located in said restricted portion of the air passage.

I claim:

1. In a tentering machine, the combination 60 of a casing, having a restricted passageway formed by a pair of walls disposed relatively close together and extending longitudinally of said casing, means for supporting a strip of material in said passageway, and means for forcing air through said passageway in

a direction transversely of the strip of material.

2. In a tentering machine, the combination 70 of a casing, having a restricted passageway formed by a pair of walls disposed relatively close together and extending longitudinally and continuously from end to end of said casing, means for supporting a strip of material in and advancing said strip longitudinally through said restricted passageway, 75 and means for forcing air through said restricted passageway in a direction transversely of the strip of material.

3. In a tentering machine, the combination 80 of a casing, having a restricted passageway formed by a pair of walls disposed relatively close together and extending longitudinally and continuously from end to end of said casing, means for supporting a strip of material in and advancing said strip longitudinally through said restricted passageway, 85 means for forcing air through said restricted passageway in a direction transversely of the strip of material, and means for heating the air.

4. In a tentering machine, the combination 90 of a casing, having a restricted passageway formed by a pair of walls disposed relatively close together and extending longitudinally and continuously from end to end of said casing, means for supporting a strip of material in and advancing said strip longitudinally through said restricted passageway, 95 means for forcing air through said restricted passageway in a direction transversely of the strip of material, and means for heating the air. 100

5. In a tentering machine, the combination 105 of a casing, having a restricted passageway formed by a pair of walls disposed relatively close together and extending longitudinally and continuously from end to end of said casing, means for supporting a strip of material in and advancing said strip longitudinally through said restricted passageway, 110 means for circulating air in said casing in a direction transversely of the casing, and means for directing the circulating air into said restricted passageway at one open longitudinally extending side thereof, whereby said air is caused to pass through said passageway in a direction extending transversely of the strip of material therein.

6. In a tentering machine, the combination 115 of a casing, having a restricted passageway formed by a pair of walls disposed relatively close together and extending longitudinally and continuously from end to end of said casing, means for supporting a strip of material in and advancing said strip longitudinally through said restricted passageway, means for circulating air in said casing in a direction transversely of the casing, means for directing the circulating air into said restricted passageway at one open longitudinally extending side thereof, whereby said air is caused to pass through said passageway in a direction extending transversely of the strip of material therein, and means for heating the air in circulation.

6. In a tentering machine, the combination 125 of an elongated casing, having a restricted passageway formed by a pair of walls disposed relatively close together and extending longitudinally and continuously from end to end of said casing, means for supporting a strip of material in and advancing said

- strip longitudinally through said passageway, means at spaced intervals along said casing for circulating air in a direction transversely of said casing, and means for directing the circulating air into said passageway at a longitudinally extending open side thereof, whereby the air is caused to pass through said passageway in a direction extending transversely of the strip of material.
- 5 7. In a tentering machine, the combination of an elongated casing, having a restricted passageway formed by a pair of walls disposed relatively close together and extending longitudinally and continuously from end to end of said casing, means for supporting a strip of material in and advancing said strip longitudinally through said passageway, means at spaced intervals along said casing for circulating air in a direction transversely of said casing, means for directing the circulating air into said passageway at a longitudinally extending open side thereof, whereby the air is caused to pass through said passageway in a direction extending transversely of the strip of material, and means for heating the air in circulation.
- 10 8. In a tentering machine, the combination of an elongated casing, a transversely extending partition in said casing whereby said casing is divided into separate compartments, a restricted passageway extending longitudinally of said casing and through said transverse partition, means in each compartment for circulating air therein in a direction transversely of said casing and transversely through the portion of said restricted passageway lying in each of the respective compartments, the air currents passing in opposite transverse directions in the portions of the passageway lying within the respective compartments.
- 15 9. In a tentering machine, the combination of an elongated casing, a transversely extending partition in said casing whereby said casing is divided into separate compartments, a restricted passageway extending longitudinally of said casing and through said transverse partition, means in each compartment for circulating air therein in a direction transversely of said casing and transversely through the portion of said restricted passageway lying in each of the respective compartments, the air currents passing in opposite transverse directions in the portions of the passageway lying within the respective compartments, and means in each compartment for heating the air in circulation.
- 20 10. In a tentering machine, the combination of a casing, a transversely extending partition in said casing dividing said casing into separate compartments, a restricted passageway extending longitudinally of said casing and through said partition, the opposite longitudinally extending sides of said passageway being open, means for supporting a strip of material in and advancing said longitudinal strip through said passageway, means in the respective compartments for circulating air in opposite transverse directions in the respective compartments, and means at opposite open sides of the portions of the passageway lying within the respective compartments, for directing the oppositely moving currents of air into the respective portions of the restricted passageway.
- 25 11. In a tentering machine, the combination of a casing having an air passage formed therein and a restricted passageway formed in said air passage and extending longitudinally and continuously from end to end of the casing, means for circulating air through the air passage and the restricted passageway included therein in a direction transversely of the casing, means for supporting a strip of material within the restricted passageway, and means within the said restricted passageway for heating the air passing therethrough.
- 30 12. In a tentering machine, the combination of a casing having an air passage formed therein and a restricted passageway formed in said air passage and extending longitudinally and continuously from end to end of the casing, means for circulating air through the air passage and the restricted passageway included therein in a direction transversely of the casing, means for supporting a strip of material within said restricted passageway, means in the air passage for heating the air in circulation, and means within the said restricted passageway for boosting the temperature of the air as it passes therethrough.
- 35 130 ALPHEUS O. HURXTHAL.
